AUTOMATIC FIREARM

Marc Birkigt, Bois-Colombes, France

Application April 16, 1938, Serial No. 202,546
In Belgium February 11, 1938

4 Claims. (Cl. 42-3)

The present invention relates to automatic firearms and especially, although not exclusively, to automatic quick firing guns to be mounted on aircrafts.

5 My invention is concerned with guns of this type having a breech structure movable axially with respect to the gun tube and constituted by two elements movable axially with respect to each other, one of these elements constituting the breech block proper and the other carrying the firing pin. These two elements are provided with locking means arranged in such manner that, as long as the breech block proper is not in firing, or front position (in which it closes the 10 rear end of the gun tube), the two elements are interlocked, whereas, when said breech block comes into said firing position, it is locked to the fixed casing but the firing pin carrier is released and can therefore move forward a certain distance under the effect of a counter-spring associated with the breech structure and of the inertia of the whole, whereby the firing pin can strike the cartridge.

The object of the present invention is to provide a gun of this type which is better adapted to meet the requirements of practice and, in particular, in which the firing safety is considerably increased so as to eliminate any possibility of accident.

25 With this main object in view, the essential feature of the present invention consists in interposing between the two above mentioned elements of the movable breech structure, elastic means for urging the firing pin carrier toward the front of the firearm, with respect to the breech block proper.

Other features of the present invention will result from the following detailed description of a specific embodiment thereof.

30 A preferred embodiment of the present invention will be hereinafter described, with reference to the accompanying drawing, given merely by way of example, and in which:

Fig. 1 is an elevational view, partly in axial vertical section, of the breech mechanism of an automatic gun for use on an airplane, made according to the present invention;

Fig. 2 is a similar view of the same breech mechanism, showing other relative positions of the parts, corresponding to another time of the operation of said mechanism;

Fig. 3 is a sectional view on the line III-III of Fig. 1;

Fig. 4 is a vertical sectional view on the line 45 IV-IV of Fig. 1;

Fig. 5 is a partial vertical section on the line V-V of Fig. 1.

In the embodiment of my invention illustrated by the drawing, the rear part of the barrel or tube 1 of the gun carries, fixed thereto, a breech casing 2. This breech casing is provided with a cartridge feeding slot 3 at the top and another slot 4 at the bottom, for the ejection of the cartridge cases having been fired.

A breech structure is mounted in said breech casing and said breech structure is constantly urged toward the front, that is to say toward the rear end of tube 1 by a counterspring 5.

This breech structure is made of two elements 10 relatively slidably with respect to each other in the axial direction.

One of these elements, to wit 6, constitutes the breech block proper. The front end of said breech block is adapted to force and wedge the cartridges successively into the chamber of the 20 gun tube, in the usual manner.

The other breech element constitutes the firing pin carrier. Specifically, as shown by the drawing, it is constituted by two bars 9 located each on one side of the breech block 6, said bars being 25 interconnected, preferably at their front parts, by a cross piece 10, which carries the firing pin 11.

The breech block 6 carries locking means, constituted, in the example that is considered, by a 30 pawl 7 pivoted at its front part to said breech block and adapted to occupy either of two different positions, to wit an upper position (Fig. 2) and a lower position (Fig. 1).

When locking pawl 7 is in its lower position 35 it locks the breech block 6 (in the front or firing position thereof) to the breech casing 2. The top projection of the free end of pawl 7 is, in the lower position, disengaged from the recess of part 9 which terminates at 8, and therefore permits said part 9 to slide along the breech block 6 in the frontward direction, under the effect of the counter-spring 5 which bears against cross piece 10 associated with bars 9. As a result of this supplementary movement of parts 9 and 10, 40 the firing pin 11 carried by piece 10 strikes the cartridge.

I provide means for driving back the firing pin carrying structure 9-10 immediately upon the firing of a cartridge. Such means may, for instance, consist of a piston and cylinder system 12-13 the movable part of which is rigid with a push piece 14 adapted to cooperate with said structure 9-10, so as to push it rearwardly under the effect of the burnt gases.

As soon as, in the course of this rearward movement, system 9-10 reaches the position in which its lower recess comes opposite pawl 7 (that is to say the position in which the end of pawl 7 is located opposite the inclined edge 8 of said recess) said pawl is allowed to pivot upwardly, under the effect of the upward component of the thrust exerted upon bevel surface 15. This unlocks the breech block 6 from the breech casing 2 and interlocks the breech block 6 and the sliding structure 9-10.

The whole of the breech structure thus moves toward the rear, compressing the counter spring 5 until said spring first stops and then reverses this movement of the breech structure, finally bringing back the parts into their initial positions after the cartridge case has been ejected and a fresh cartridge introduced into the gun chamber.

According to the essential feature of the present invention, I interpose, between the elements of the breech structure, that is to say between the breech block 6 and the firing pin carrying structure 9-10, elastic means for urging said firing pin carrying structure toward the front of the firearm when the breech block 6 is fixed in position.

With such an arrangement, during the first portion of the recoil movement of structure 9-10, that is to say while said structure 9-10 is moving back toward its interlocked position with the breech block 6 (then locked in firing position) said structure 9-10 is compelled to overcome the resistance of said elastic means, which then act in the same manner as the counter spring 5.

These elastic means, such as constituted by spring 17, reduce the risks of an accidental unlocking of the breech block 6 before the proper time. Such risks are particularly serious when the gun is firing vertically since, in this position, bars 9 might, in the absence of such elastic means and under the effect of gravity, slightly compress the counter spring 5 and produce the disengagement of the breech block before the shot has been fired. Also, in the case of hanging fire, said bars 9 might, by rebounding, accidentally produce the disengagement of the breech block 6.

In both of these cases, a premature disengagement of the breech block would permit the latter to recoil immediately upon the firing of the shot, when the thrust exerted by the burnt gases through the cartridge case on the front end of the breech block 6 is considerable, thus risking deterioration of the firearm.

As such a premature disengagement of the breech block from locking engagement with the breech casing is opposed by the elastic means 17, the firing safety is greatly improved.

For practical purposes, I may employ many embodiments of such elastic means, and I have found that it is advantageous to employ the specific arrangement illustrated by the drawing.

In this case, I provide, in bars 9, slots 9' adapted to accommodate lugs 16 rigid with the breech block 6, so that said lugs can move in said slots in the course of the relative axial displacements of said breech block and said bars. The springs 17 above mentioned are mounted in said slots, being constituted by coil springs the front ends of which bear against the front ends of said slots, that is to say upon the respective bars 9, while the rear ends of said springs 17 bear against said lugs 16. This spring arrange-

ment opposes recoil displacement of structure 9-10 with respect to the breech block 6.

In a general manner, while I have, in the above description, disclosed what I deem to be practical and efficient embodiments of the present invention, it should be well understood that I do not wish to be limited thereto as there might be changes made in the arrangement, disposition, and form of the parts without departing from the principle of the present invention as comprehended within the scope of the appended claims.

What I claim is:

1. An automatic firearm which comprises, in combination, a tube, a breech structure movable with a longitudinal reciprocating motion in line with said tube at the rear thereof, a stationary casing rigid with said tube for guiding said breech structure, said breech structure including a breech block proper and a firing pin carrier movable longitudinally to a limited extent with respect to said breech block, means operative by the longitudinal movement of said breech structure for interlocking the two elements thereof until said breech block reaches its end frontward position, means including said first-named means and a notch in said casing for locking said breech block in said end position and simultaneously disengaging the firing pin carrier from said breech block at the end of the frontward movement of said breech block, whereby said firing pin carrier can further move frontwardly, said last mentioned means being adapted to act in a reverse manner upon the return movement of said firing pin carrier, means for driving back said firing pin carrier upon the firing of a shot, and elastic means between said breech block proper and firing pin carrier for urging said firing pin carrier frontwardly with respect to said breech block.

2. An automatic firearm which comprises, in combination, a tube, a breech structure movable with a reciprocating motion in line with said tube at the rear thereof, a stationary casing rigid with said tube for guiding said breech structure, said breech structure including a breech block proper and a firing pin carrier movable longitudinally to a limited extent with respect to said breech block, cooperating means, provided on said breech structure elements and said breech casing and operative by relative displacements of said elements, for interlocking the two breech structure elements as long as said breech block has not reached its extreme position toward the front and locking said breech block in said casing when said position is reached while uncoupling said firing pin carrier from said breech block, whereby said firing pin carrier can further move frontwardly, said last mentioned means being adapted to have their action reversed for inverse movements of the breech elements, means for driving back said firing pin carrier upon the firing of a shot, and spring means between said breech block proper and firing pin carrier for constantly urging said firing pin carrier frontwardly with respect to said breech block.

3. An automatic firearm which comprises, in combination, a tube, a breech structure movable with a reciprocating motion in line with said tube at the rear thereof, a stationary casing rigid with said tube for guiding said breech structure, said breech structure including a breech block proper and a firing pin carrier movable longitudinally to a limited extent with respect to said breech block, a pawl carried by said breech block and notches with inclined edges

provided on said firing pin carrier and said breech casing adapted to cooperate successively with said pawl under the effect of relative movements of said breech structure in said casing for interlocking the breech block proper and the firing pin carrier as long as said breech block has not reached its extreme position toward the front and locking said breech block in said casing when said position is reached while simultaneously uncoupling said firing pin carrier and said breech block, whereby said firing pin carrier can further move frontwardly when said breech block is stopped, said pawl and notches being adapted to have their respective actions reversed when the movements of the breech block proper and firing pin carrier are reversed, means for driving back said firing pin carrier upon the firing of a shot, and spring means interposed between said breech block and said firing pin carrier for constantly urging said firing pin carrier frontwardly with respect to said breech block.

4. An automatic firearm which comprises, in combination, a tube, a breech structure movable with a reciprocating motion in line with said tube at the rear thereof, a stationary casing rigid with said tube for guiding said breech structure, said breech structure including a breech block proper provided with a longitudinally elongated transverse slot, two longitudinal bars slidable on either side of said breech block in the longitudinal direction, a transverse member carrying a

firing pin and rigidly interconnecting said two bars extending through said slot, whereby the whole of said bars and said transverse member can slide longitudinally to a limited extent with respect to said breech block, cooperating means 5 provided on said breech block proper, said bars and said breech casing and operative by relative displacements of said breech block proper, bars and breech casing, for interlocking said breech block and said bars as long as said breech block 10 has not reached its extreme position toward the front and locking said breech block in said casing when said position is reached while simultaneously uncoupling said bars from said breech block, whereby said bars and said transverse 15 member can further move frontwardly, said last mentioned means being adapted to have said actions reversed for reversed directions of movement of said breech block proper and bars, means for driving back said bars and said transverse 20 member upon the firing of a shot, a counter-spring for urging said bars and transverse member frontwardly, said bars being provided with longitudinal slots, lugs carried by said breech block engaging in said last mentioned slots respectively, and springs housed in said slots between the front ends of said slots and said lugs respectively for constantly urging said bars frontwardly with respect to said breech block.
